United States Patent Office.

WILLIAM SMITH HALL, OF QUINCY, MASSACHUSETTS.

Letters Patent No. 91,123, dated June 8, 1869.

IMPROVEMENT IN HOMOMOTIVE.

The Schedule referred to in these Letters Patent and making part of the same.

To all whom it may concern:

Be it known that I, WILLIAM SMITH HALL, of Quincy, in the county of Norfolk, and State of Massachusetts, have invented a Homomotive; and I do hereby declare that the following, taken in connection with the drawings, which accompany and form part of this specification, is a description of my invention sufficient to enable those skilled in the art to practise it.

United States Letters Patent, No. 65,665, dated June 11, 1867, and No. 86,833, dated February 9, 1869, have been granted to me for certain improvements in treadle-mechanisms for operating machines.

My first patent (65,665) relates particularly to, and covers a peculiar system of spring-pawl levers, ratchet-and-pawl mechanism, and double set of treadle-levers, pawl-levers, &c., so arranged that the actuated wheel or shaft may be driven by either or by both treadles, and by any extent of movement of either or both, and my second patent (86,833) relates particularly to, and covers the combination of the invention shown in the first patent, with a peculiar pawl-and-clutch mechanism, and the peculiar arrangement of a momentum-wheel, and other details of the mechanism.

These inventions were designed for driving any light mechanisms capable of being advantageously operated by foot-power, and the peculiar organization shown in the last patent was designed by me with particular reference to the adaptation of the inventions to driving light vehicles by hand or by foot-power, or by both combined.

My present invention relates to this adaptation, and consists primarily in a carriage having this mechanism applied to it, in such manner that the carriage may be propelled by hand or by foot, or by both the hands and feet, the extent of play or movement of the impelling-hand or foot being variable at will, there being no cranks and no dead-centres, and each impelling-lever being automatically returned to its normal position without respect to the extent of its actuating-movement.

The drawings represent a carriage embodying the invention.

A shows the vehicle in side elevation.

B is a front view.

C, a plan, the carriage-body being removed.

a denotes the carriage or truck-frame, having axles b e mounted respectively on wheels d e.

The rear wheels e are fixed to their axle c, said axle turning in bearings f on the under side of the perches of the frame a.

Said shaft or axle carries a gear-wheel, g, meshing into and driven by a pinion, h, on a shaft, i, that carries a momentum-wheel, k, and this shaft i carries a pinion, l, meshing into and driven by a driving-gear, m, on a shaft, n, each shaft, i n, turning in bearings on the under side of the frame a.

The gear-wheel m is fixed to, or preferably forms a direct part of a pawl, or pawl-driven wheel o, having laterally-projecting rings, or flanges p on its opposite sides, with which flanges engage two clutch or friction-pawls, or gripes q.

Each of these pawls is hung at the end of a pawl-lever, r, fulcrumed and rocking freely on the shaft n, the opposite arm of the lever being attached to one end of a spring, z², whose other end is attached to the frame a, the stress of each spring returning its lever to normal position when released.

Each pawl, or gripe q, is composed of two pins j, projecting from an arm, s, said arm having an oblong slot near its outer end, through which passes the screw-pin t, by which it is hung to the pawl-lever, and the pins j j embrace the adjacent flange of the driving-wheel.

Each arm s is pressed in a direction opposite to that in which it moves in driving the wheel, by a slight spring, u, the slot enabling the arm to assume a position in direct line with the pawl-lever, or a position angular thereto.

When the spring u throws the arm into inclined position, the two clutch-pins j hug the flange of the wheel, so that if the pawl-attached arm of the lever is moved in the opposite direction, or in a direction to keep the arm so inclined, the pins will carry the wheel with them, the lever and wheel having the same centre of movement, while, if the movement of the lever be reversed, friction of the pins against the flange will bring the arm s into line with the lever-arm, and the pins will slip upon the flange, or the flange will run between the pins without movement being imparted by them to the wheel, and without the pins impeding the free rotative movement of the wheel.

The mechanism thus described, for driving the shaft, is identical, in its general arrangement and method of operation, with that shown in my patent, 86,833, the upper arm of each pawl-lever in said patent being connected with a treadle, by means of which either pawl may be actuated singly, or both together, the momentum-wheel, on a shaft auxiliary to the pawl-driven shaft, acting as an accumulator of the power exerted in driving the treadles.

In the carriage, I joint to the upper arm of each pawl-lever the rear end of a horizontal connecting-rod, v, whose front end is jointed to a rocker-arm, w, hung on a cross-rod, x, in front of the dasher of the carriage. The arm swings freely on this rod.

To the end of each rocker-arm w is fixed a pedal-bar, y, which projects through a hole in the dasher-board, and has, at its top, a pedal, z, preferably jointed to the bar, so as to tip freely in the direction of its length.

The rider sitting upon the carriage-seat, places his two feet upon the two pedals, and by alternately press-

ing down the pedals, pushes out each rocker-arm at the front of the carriage, thereby working the pawl-levers, and turning the driving-wheel, and (through the system of gearing) rotating the rear axle and its wheels, and propelling the carriage.

After each forward movement of either pedal, the stress of the foot being withdrawn, the spring z^2 draws back the upper arm of the pawl-lever, the connecting-rod v , and the rocker-arm, and the pedal restoring all these parts to their normal positions for a repetition of the operation.

The carriage may thus be driven by either pedal alone, by both pedals together, or by both alternately, the momentum acquired by the fly-wheel k securing ease or uniformity of movement in the carriage, and enabling it to be more easily propelled.

It will be observed that the pedal-bars are so arranged that the rider can readily push each of them forward with his feet, bracing himself against the back of the seat.

Besides the rocker-arms w , the rod x carries two upright hand-levers o^3 , projecting from sleeves turning upon the rod, each sleeve having at one end a clutch-tooth or shoulder, which engages with a tooth or shoulder on the adjacent end of the sleeve, by which the rocker-arm is hung upon the rod.

A cord, a^2 , is fastened to the upper end of each hand-lever, and the rider grasping a cord in each hand, and pulling the cords towards him, bracing his feet against the dasher, effects the same movement of the rocker-arms that is effected by the feet in action with the pedals.

The hand-levers and pedals may be used in conjunction, but it will be obvious that they can be used to better advantage independently. They enable the rider, however, to use either his hands or his feet, as he may be best able to do, or to change from one to the other, as circumstances or fancy may dictate or require.

When the hand-levers are not in use, they may be swung down below the rod x , as seen at B, one of them being also shown as thrown down at A.

Either hand-lever may be actuated alone, or both together, or alternately, and in using either feet or hands, it will readily be seen that the movement of the pedal or of the hand-lever may be arrested at any point short of the full stroke thereof, the clutch-pins returning from any position to normal position.

As the clutch-pins grip the driving-wheel normally, and in their downward movement, they also act as stops, to prevent back movement of the driving-wheel and of the carriage-wheels driven thereby. This will prevent the carriage from running backward when upon an incline.

As it is often necessary to "back," however, I arrange the gearing so that the same movement of the pawl-driven wheel may propel the carriage either forward or backward. For this purpose, I place the pinion h loosely upon the shaft i , and also place upon the same shaft another loose pinion, b^2 , and between these two pinions, I place a clutch, c^2 , splined to and sliding upon the shaft i , and operated by one arm of a shipper-lever, d^2 , whose other arm has a fork or crotch, with which one arm of an upright hand-lever, e^2 , engages, this lever extending up on one side of the seat, as seen at A.

By means of the lever e^2 the clutch-wheel may be thrown into engagement with clutch-pins on either pinion.

The pinion b^2 is geared to a pinion, f^2 , on the shaft, or axle c , by an intermediate g^2 , so that the same motion of the driving-gear that imparts forward movement to the rear wheels, when the clutch is connected with the pinion h , imparts rotary movement to the same wheels when the clutch is connected with the other pinion b^2 .

By bringing the clutch midway between the pinions, the carriage may be drawn or pushed in either direction without reference to the mechanism to be actuated by the rider.

A steering-mechanism, by which the rider may turn the front wheels by hand or foot, may be applied to the carriage, as follows:

The front axle, upon which the wheels turn, has, at its centre, a plate, h^2 , through which the transom-bolt i^2 passes.

Just back of the transom-bar is a shaft, k^2 , on which is a worm-wheel, l^2 , into the groove or between the threads of which projects, from the plate h^2 , a pin, m^2 .

At the front of the carriage is a vertical shaft, n^2 , turning in bearings fixed to the carriage-body.

At the top of this shaft are arms o^2 , at the ends of which are cords p^2 , to be grasped and operated by the hands of the rider, or a lever-arm, t^2 , may be jointed to the top of the shaft, to turn it.

At or near the foot of the shaft are two other arms q^2 , to the opposite ends of which are jointed pedal-bars r^2 , projecting through slits in the dasher-board.

Below the arms q^2 another arm, s^2 , is fixed to the shaft n^2 , to the end of which arm the end of a rocker-arm, u^2 , turning on a horizontal pin, w^2 , is connected by a link, v^2 ; this rocker-arm u^2 carrying a segment-gear, x^2 , the teeth of which mesh into a pinion, y^2 , on the shaft of the worm-wheel.

Now, as the shaft n^2 is turned in either direction by the hand or foot of the rider, the movement of the arm s^2 turns the gear x^2 , which turns the shaft of the worm-wheel, the rotative movement of the worm-wheel moving the pin m^2 , and thereby turning the front axle, and changing the direction of movement of the carriage.

The thread of the worm-wheel is of such degree of pitch that it holds the pin and front wheels in any position, the change of direction being produced only by turning the shaft.

The movement of the carriage may be arrested by brake-shoes a^3 b^3 , at the ends of a slide-bar, c^3 , which is held back by a spring, d^3 , and is pressed out by a rocker-lever, one arm, f^3 , from which, projects up at the side of the seat, to be operated by the hand of the rider, while another arm, g^3 , projects through into the front of the carriage-seat, to be operated by the foot of the rider.

The bar is moved up towards the wheels by an arm, i^3 , which enters a hole in the brake-bar between two slots, through which pass the pins that hold the bar.

By forward movement of arm f^3 , by hand or by depression of the arm g^3 , the bar is slid towards the wheels, bringing one brake-shoe against the periphery of the outer wheel, and the other against the periphery of the fly-wheel, thereby arresting the movement of both wheels.

It will be observed that the fly-wheel shaft is arranged between the shaft of the pawl-driven wheel and the shaft or axle of the rear carriage-wheels.

The fly-wheel may, however, be placed on an auxiliary shaft, not forming an intermediate, but employed simply as a shaft for carrying the momentum-wheel.

Each pedal-bar y is preferably made removable from the rocker-arm w , so that when the carriage is being driven by hand-power alone, the pedal-bars can be slipped from position, the space in front of the seat not being then obstructed by reciprocating pedals.

I claim—

1. A carriage constructed and arranged to be driven by hand or foot, or hand and foot, by means of a system of ratchet-and-pawl clutch mechanism and gearing, substantially as shown and described.

2. Also, the organization of mechanism for changing the direction of rotation of the shaft of the actuated carriage-wheels, substantially as shown and described.

3. Also, the organization of mechanism for steering or changing the direction of movement of the front wheels, substantially as shown and described.

4. Also, in combination with a carriage, which may be driven by hand or foot, or both, removable pedals, substantially as described.

5. Also, in combination with a carriage, which may be driven by hand or foot, or both, hand-operated arms

or levers, which may be thrown into position to be operated, or out of such position, substantially as described.

WM. SMITH HALL.
